COMPOSITE ELECTRICAL SIGNALING AND INTER-COMMUNICATING SYSTEM

Reagan G. Brown, Oklahoma City, Okla.

Application June 6, 1955, Serial No. 513,540

17 Claims. (Cl. 179—5)

The present invention relates to robbery and burglary alarm systems, and more particularly to a composite electric signaling and inter-communicating system in which the alarm signals and the inter-communicating telephones are operated over conductors common to both.

Alarm systems such as are commonly used to foil robbery attempts in banks, ticket offices, pay windows, etc., are usually operated by a manually operated switch or button. This type of an alarm system has the disadvantage occasioned by the attendant's failure to sound the alarm due to the threats of bodily harm to the attendant, made by the robber who is watching every move of his victim.

Therefore it is the primary object of this invention to provide an alarm system and connecting inter-communicating telephones in which the station under attack will automatically audibly signal a central watch station or stations, such as guard stations, or the police station, or both, by an act of the attacker or by an apparently normal act of the attendant.

An additional object of this invention is to provide an alarm system of this class which will silently indicate to the attendant that the alarm is being sounded.

An additional object is to provide a composite alarm system which operates equally as well when used as a night or holiday protective system as when used during business day hours.

Another object is to provide an alarm system which automatically actuates audible and visual signals indicating defects which make the system ineffective.

Another object of this invention is to provide an alarm system of this class which features a means of indicating defects and the nature of the same within the system without sounding an alarm in the central watch station.

Still another object of the instant invention is to provide a means of eliminating false alarms due to defects of the conductors leading to or from the bells or telephones.

Another important object of the instant invention is to provide an emergency source of power for operating the system and means for automatically placing the same in operation upon failure of the principal source of supply and which means will automatically restore the system to the original source of power upon its return to normalcy.

An additional object of this invention is to provide a means of audibly signaling attendants that the emergency source of power is being used.

Yet another important object is to provide an alarm system of this class which features an alternating low frequency current for sounding an alarm in the watch stations, separate and distinct from the direct current sources normally used in the protective operational features of the system, thereby avoiding possibility of false alarms at the watch stations which is ordinarily experienced in direct current open and closed circuit alarm systems.

Another object is to provide an alarm system of this

2

class which includes a means of visual and audible inter-communication.

Still another object is to provide an alarm system of this class which includes a means for balancing the impedance of the audible or telephone circuit to thereby eliminate inductive disturbances and improve telephonic communication.

An additional object is to provide an alarm system of this class in which is included a resistance of fixed value in the conductor line, thereby establishing fixed current values in relay adjustments for stable operation.

Another object is to include in this alarm system a fixed resistance whereby connecting the same across the conductor line disconnects the inter-communicating means and substitutes a facsimile of the normal line condition for determining character and location of line trouble.

The present invention accomplishes these and other objects by providing an alarm system containing a series of relays maintained and operated from a commercial alternating current source of supply, such as 110 volt, when the system is in operation and connected with a plurality of telephones connected in multiple series and remotely located at a central watch station. Means including lamps and a marginal relay indicates defects and the nature of the same within the system. A make-before-break switch associated with the primary relay, converts the system to battery operation in connection with a battery ringing converter in the event of commercial current failure, and restores it upon resumption of the same. The marginal relay further provides a means of signaling attendants by operation of telephone switch hooks for inter-communication without disturbing the alarm system, and provides a balanced impedance for clearer telephonic communication. A subcycle ringer is actuated by any one of three alarm key contacts, and a relay to ring warning bells until the same are silenced by the removal of a telephone from its hook. An electric timer connected with a normally open circuit and a normally closed circuit, associated with the alarm key, makes contact to sound an alarm upon opening the closed circuit, or upon closing the open circuit.

Other objects will be apparent from the following description when taken in conjunction with the accompanying single sheet of drawings, wherein:

Figure 1 illustrates the invention by usual schematic circuit symbols; and

Figure 2 is a horizontal cross-sectional view of an alarm switch as used by the system.

Like characters of reference designate like parts in those figures of the drawings in which they occur.

In the drawings:

The circuit of the present invention is connected to a source of commercial alternating current designated by terminals 5 and 6, through a suitable fuse 7 and switch box, not shown. The system also includes a source of direct current 9, comprising a transformer 10 and a full-wave rectifier 11, which may be a dry-disc rectifier, the output terminals of which are bridged by condensers 12 and an impedance coil 13 to smooth out undulations in the output current of the rectifier.

The above described arrangement is conventional with many electrical alarm systems and constitutes no part of the present invention other than to serve as a suitable source of filtered direct current.

The details of the alarm system will be best understood by a description of each typical operation.

Normal operation

Current from the output terminals of the rectifier 11, through the windings of a first relay A, maintains the same operated, closing the springs 20 and 21 with their

respective make contacts 22 and 23. A circuit may now be traced from spring 20 and its make contact 22 over conductors 25 and 26, spring 27 and its make contact, conductor 28, through one winding of a double wound relay B, conductor 29 and its make contact with spring 30, conductor 31, through spring 32 and its make contact 33 of test key C, conductor 34, through a desired number of low frequency alternating current telephone alarm bells D connected in multiple series located in selected location 39, conductor 35 and its make contact 36 with spring 37 of test key C, conductor 38 through spring 40 and its make contact, conductor 41 through a second winding of the relay B, over conductor 42, through rheostat E, conductor 44, through the winding of marginal relay F, through contact 23 to spring 21 over conductor 43. Relays A and B operate over this circuit. Relay F remains unoperated, due to the high resistance of the normal line condition.

Sounding an alarm

When the present system is installed in a desired location, for example a bank, or the like, two types of alarm keys are installed. One type may be a simple manually operated key as indicated by the letter G, which is preferably installed in the bank vault. The other key or switch is indicated generally as at H, and is illustrated in cross-sectional detail (Fig. 2). The key H is preferably installed under or within a money drawer of the teller's cage, not shown, with only the spring 45 and its make contact bar 46 projecting into the drawer. The key H is inactivated or held open by insulating material, such as currency 47, flatly disposed between the spring 45 and its make contact 46, which insulates or breaks the key contact points. The key H further includes a resilient member 48 bearing against the upper surface of the make contact bar 46. The purpose of the member 48 is to frictionally engage and securely retain the insulating material or currency 47 in position between the contact points to prevent accidental removal of the same, thus sounding a false alarm. Suitable insulation 49 separates the juncture of the spring 45, the member 48, and the contact bar 46, to spacedly separate the terminal ends of the contacts 45 and 46.

An alarm may be sounded by manually depressing spring 50 with its make contact of alarm key G or by the manual removal of the currency 47 between the contacts 45 and 46 of the key H, thus closing the contacts to actuate the alarm circuit. A circuit may then be traced from spring 20 and its make contact 22 through the winding of a second relay J over conductor 25, through alarm key contacts G or H over conductors 51 and 52, through spring 53 and its make contact 56 in switch hook P, through contact 23 to spring 21 over conductors 54 and 43. Operation of relay J by the above traced circuit moves springs 27-30 and 40-55 to their respective contacts 57-58 and 60-61 to apply an alternating ringing current from a sub-cycle ringer K to the telephone bells D. The purpose of spring 55 and its contact 61 is more fully explained hereinbelow. The ringer K, which is preferably a 20 or 30 cycle ringer, is directly connected in a conventional manner to a commercial current and a circuit may be traced from one terminal 62 of the ringer K over conductor 63 and through its make contact with spring 64, over conductor 65 and through its contact 58 with spring 39, conductor 31 and through its contact 32 with spring 33 of test key C through bells D over conductors 34 and 35, through contact 36 with spring 37 in test key C, over conductor 38, through spring 40 and its contact 60, over conductor 66, through spring 67 and its make contact to the terminal 68 of ringer K over conductor 69.

The cycle ringer K continuously rings the bells D until telephone T is removed from the switch-hook P. Telephone T is normally located in the bank vault with alarm key G. When an alarm is sounded by the removal of

the currency 47 from key H, the alarm bells ring continuously thus indicating to the guards or attendants that a robbery is taking place. When the alarm is sounded by manually closing the points of alarm key G within the vault, the telephone may be alternately removed and replaced on the switch-hook P to intermittently ring the alarm bells thus indicating to the guards or attendants that telephonic communication is desired. In this instance the guards may be informed of the emergency and the nature of the same by telephone. It seems obvious that the telephones T and U are not to be used except in an emergency because removal of the telephone T from its switch-hook P renders the system inoperative. Removing telephone T from the hook P releases spring 53 from its make contact to break the circuit traced hereinabove by the contacts of the alarm key G or H to restore relay J and return springs 27-30 and 40-55 to their respective make contacts for the normal circuit operation as traced hereinabove, providing current 20 for telephonic inter-communication between telephone T and telephones U. Operating switch-hook P also closes spring 59 with the contact 56 to short the winding of relay F over a circuit traced from contact 56 through spring 59, rheostat E and the winding of relay F over conductors 70, 42, 44, and 54, thereby preventing the operation of relay F which also establishes a balanced impedance circuit for telephone communication, eliminating inductive disturbances. Operation of relay J illuminates alarm lamp L, preferably located in the bank vault, for indicating an alarm is being sounded over a circuit traced from spring 20 and contact 22, over conductors 25 and 26, through spring 27 and its contact 57 through lamp L over conductors 72, 73 and 43 through contact 23 to spring 21.

35 A conventional timer is installed in a conventional manner within the system for controlling the times the vault, not shown, may be opened. The timer is connected with the system through a relay Y over a normally closed circuit and a normally open circuit. The closed 40 circuit may be traced from spring 20 and its contact 22 over conductors 25 and 112 through the windings of relay Y, through vault door spring 114 and its contact 115, over conductor 52, through spring 53 and its contact 56, over conductors 54 and 43 to spring 21 through its contact 23. This circuit remains closed during the time 45 the vault doors are left closed and the timer is not making contact with the conductors of the system, which times are predetermined as is conventional with timers of this class. This above described closed circuit maintains the relay Y operated. If at any time either of the 50 vault door contacts are opened before the time set for the timer to operate, vault door spring 114 breaks the closed circuit in being removed from contact 115 restoring relay Y allowing spring 116 to make with its contact 117, thus closing the alarm circuit as traced hereinabove for the alarm keys.

The timer X is connected with the conductor 113 and to the conductor 52 by conductor 118. At a predetermined time the contact 119 makes contact which closes 60 a companion circuit from relay Y over conductor 113, through contact 119 of the timer X and to conductor 52 over conductor 118, thus closing the circuit traced hereinabove for the vault door maintaining the relay Y operated and permitting the opening of the vault door and breaking the contacts 114 and 115 without sounding an alarm.

Line or telephone trouble

An open or break, for example in the conductors 34, 70 35, or telephone U, restores relay B releasing springs 71 and 74 from their make contacts into engagement with their respective contacts. A circuit may then be traced through spring 20 and its contact 22, conductors 25 and 26, spring 27, conductors 28 through spring 71 and contact 75, over conductor 76, through spring 77

and its contact key M, through the winding of buzzer N through contact 23 to spring 21 over conductors 78, 73 and 43 operating the buzzer N. Under these conditions a companion circuit may also be traced from spring 71 through contact 75, over conductor 79, spring 74 through contact 80, conductor 81 through trouble-indicating lamp O and contact 23 to spring 21 over conductors 73 and 43 illuminating lamp O for visual indication of a break in the line. Opening key M by manually moving spring 77 from its contact, silences the 10 buzzer N. Repair of the line break restores the circuit to normal to operate relay B and extinguish lamp O.

Similarly when the resistance of the line as disclosed above in normal operation drops or is low, marginal relay F operates and remains operated to visually and audibly indicate a short or ground in the system by the following circuit which may be traced through spring 20 and its contact 22, over conductors 25, 82, through spring 83 and its make contact, over conductors 84, 79, and 76, through spring 77 and its contact in key M, 20 through the winding of buzzer N, through contact 23 to spring 21 over conductors 78, 73 and 43, thus activating buzzer N to complete the audible warning. The visual signal or warning which illuminates a trouble-indicating lamp Q comprises a companion circuit which may be traced from conductor 84 through spring 74 and its make contact, through lamp Q and contact 23 to spring 21 over conductors 85, 73 and 43, illuminating lamp Q. When either lamp O or Q is illuminated and buzzer N is operating indicating a line break, short or ground, key C may be manually operated to determine whether or not the defect trouble is within the conductors 34 or 35 leading to or in the telephones U. Springs 32 and 37 of test key C are moved from their respective make contacts 33 and 36 to make contact with the 35 terminal ends of a resistor R of fixed value, thus disconnecting the central watch station 39 and simulating normal line resistance, whereby the lamps O or Q are extinguished and the buzzer N silenced by the re-operation of relay B or the restoring of relay F, thereby indicating 40 the nature of the line trouble.

Commercial current failure

In the event of failure or interruption of the commercial alternating current, an emergency battery S is provided which is connected to the conductors 25 and 43 by a make-before-break switch I associated with the springs 20 and 21 of the relay A over conductors 87 and 88 and contacts 89 and 94. As the commercial power fails, the relay A restores and the switch I makes contact engaging the current of the battery S to maintain the above described circuits. Engagement of battery S illuminates lamp V visually indicating that the emergency battery S is in use, over a circuit traced from terminal 91 over conductor 92, through lamp V to terminal 93 over conductors 73, 43 and 88. 45

Similarly when the battery S is engaged, a buzzer Z is actuated to audibly indicate that the alternating current has been off and that the setting of the timer X will need to be adjusted. The buzzer operates over a 60 circuit traced from terminal 91 over conductors 92 and 120 through contact 121 and spring 122 of buzzer Z, through the winding of buzzer Z, over conductors 123, 73 and 43, through contact 94, over conductor 88 to terminal 93. Opening of contact 121 silences the buzzer Z. 65

A battery operated ringing converter, indicated generally by the numeral 90, is provided for operating the bells D upon failure of the commercial alternating current. The battery ringing converter 90 is conventional and includes a suitable transformer, condensers, a resistor and a relay.

When relay A restores, spring 96 is released to its contact 97 to establish a circuit for the engagement of the battery ringing converter 90 when either of the alarm keys G or H makes contact, which may be traced 70

over a circuit from terminal 91 of battery S through switch I, contact 89 and the windings of a third relay W, over conductors 98 and 99, through spring 96 and its contact 97 over conductor 100, through contact 61 with spring 55 and contact 94 of the switch I to terminal 93 of battery S over conductors 101, 43 and 88. Operation of relay W moves springs 64 and 67 to their respective contacts 102 and 103 and connects the battery ringing converter 90 from the secondary winding of its transformer with the above traced bell ringing circuit over conductors 104 and 105. This circuit also supplies current for operating the battery ringing converter over conductors 106 and 107, respectively, connected with conductors 98 and 100. Upon resumption of the commercial source of power, relay A re-operates disengaging the battery S.

Inter-communication

An attendant or guard at telephones U may signal the teller in the booth or at telephone T by removal of the telephone U from its respective hook which lowers the resistance of the circuit and operates relay F, as disclosed hereinabove, operating the buzzer N and illuminating lamp Q, as disclosed hereinabove. Removal of telephone T from hook P closes spring 108 with its contact 109 to connect telephone T with the conductors 34 and 35 of the circuit over conductors 110 and 111.

Obviously the invention is susceptible to some change or alteration without defeating its practicability, and I therefore do not wish to be confined to the preferred embodiment shown in the drawings and described herein, further than I am limited by the scope of the appended claims.

I claim:

1. An alarm system, including: a source of alternating current; a source of direct current; a first relay maintained operated by said direct current; alarm bells connected in multiple series; a circuit connecting said bells closed by the operation of said first relay; a sub-cycle ringer connected with said alternating current; a second relay; an alarm key; a circuit for said second relay and said alarm key closed by actuation of said alarm key; and a companion circuit connecting said ringer with said bells for ringing the same, closed by the operation of said second relay.

2. An alarm system, including: a source of alternating current; a source of direct current including a full-wave rectifier connected with said alternating current; a first relay connected with and maintained operated by said direct current; a plurality of alarm bells connected in multiple series; a circuit for said bells closed by the operation of said first relay; a sub-cycle ringer connected with said alternating current; a second relay; an alarm key; a circuit for said second relay and said alarm key closed by the contacts of said alarm key for operating said second relay; a circuit connecting said ringer with said bells, for ringing the same, closed by the operation of said second relay; and a switch-hook in said alarm key circuit, whereby said second relay is restored by opening said switch, thereby silencing said bells.

3. An alarm system, including: a source of alternating current; means including a full-wave rectifier for changing said alternating current to a source of direct current; a first relay connected with and maintained operated by said direct current; a plurality of alarm bells connected in multiple series; a circuit for said bells closed by the operation of said first relay; a sub-cycle ringer connected with said alternating current; a second relay; an alarm key; a circuit for operating said second relay closed by the contact points of said alarm key; a circuit connecting said ringer with said bells, for ringing the same, closed by the operation of said second relay; an alarm lamp; a circuit for said lamp closed by the operation of said second relay; and a switch-hook in said alarm key circuit, whereby said

second relay is restored by opening said switch, thereby silencing said bells and extinguishing said lamp.

4. A composite electric signaling and inter-communicating system, including: a source of alternating current; a source of direct current; a first relay connected with and maintained operated by said direct current; a plurality of alarm bells and telephones connected in multiple series; a circuit for said bells and telephones closed by the operation of said first relay; a sub-cycle ringer connected with said alternating current; a second relay; an alarm key; a circuit for operating said second relay by the closing of said alarm key; a circuit connecting said ringer with said bells closed by said second relay in operated position; an alarm lamp; a circuit for said lamp closed by said second relay in operated position; and a switch-hook in said alarm key circuit, whereby said second relay is restored by opening said switch, thereby silencing said bells, extinguishing said lamp and permitting telephonic intercommunication.

5. A composite electric signaling and intercommunicating system, including: a source of alternating current; means including a full-wave rectifier supplying a source of direct current; a first relay connected with and maintained operated by said direct current; a plurality of alarm bells and telephones connected in multiple series; a circuit for said bells and telephones closed by the operation of said first relay; a sub-cycle ringer connected with said alternating current; a second relay; an alarm key; a circuit for operating said second relay by the closing of said alarm key; a circuit connecting said ringer with said bells, for ringing the same, said circuit closed by the operation of said second relay; an alarm lamp; a circuit for said lamp closed by the operation of said second relay; a closed switch-hook in said alarm key circuit, whereby said second relay is restored by opening said switch, thereby silencing said bells, extinguishing said lamp and permitting telephonic inter-communication; a marginal relay; a rheostat; and a circuit connecting said marginal relay and said rheostat in series with said bells and telephone circuit closing said circuit by the opening of said switch-hook for shorting said marginal relay and said rheostat and establishing a balanced impedance over said telephone circuit.

6. A composite electric signaling and intercommunication system, including: a source of alternating current; means including a full-wave rectifier supplying a source of direct current; a first relay connected with and maintained operated by said direct current; a double wound relay; a plurality of alarm bells and telephones connected in multiple series; a circuit for operating said double wound relay and connecting said bells and telephones, said circuit closed by the operation of the said first relay; a sub-cycle ringer connected with said alternating current; a second relay; an alarm key; a circuit for operating said second relay by the closing of said alarm key; a circuit connecting said ringer with said bells, for ringing the same, said circuit closed by the operation of said second relay; an alarm lamp; a circuit for said lamp closed by the operation of said second relay; a closed switch-hook in said alarm key circuit, whereby said second relay is restored by the opening of said switch-hook; a marginal relay; a circuit connecting said marginal relay with one winding of said double wound relay, said marginal relay normally maintained unoperated; a trouble-indicating lamp; and a circuit connecting said trouble-indicating lamp with said marginal relay, whereby said marginal relay is operated by a short or low resistance in said telephone circuit to illuminate said trouble lamp.

7. A system as claimed in claim 6: a buzzer; and a circuit connecting said buzzer with said marginal relay, whereby said buzzer is operated by the operation of said marginal relay.

8. A system as claimed in claim 7: a resistor of fixed value; and means including a test key for disconnecting said bells and telephone circuit and connecting the same through said resistor.

9. A composite electric signaling and inter-communicating system, including: a source of alternating current; means including a full-wave rectifier supplying a source of direct current; a first relay connected with and maintained operated by said direct current; a plurality of bells and telephones connected in multiple series; a circuit for said bells and telephones closed by the operation of the first said relay; a sub-cycle ringer connected with said alternating current; a second relay; alarm key means, said means including a base bar having a contact point, a spring member having a co-operating contact point, a resilient member under said spring member bearing against said base, and insulating means between said resilient member and said base for holding said key contacts open; a circuit for operating said second relay closed by the contact points of said alarm key; a circuit for connecting said ringer with said bells, for ringing the same, said circuit closed by the operation of said second relay; an alarm lamp; a circuit for said lamp closed by the operation of said second relay; and a switch-hook in said alarm key circuit, whereby said second relay is restored by opening said switch, thereby silencing said bells, extinguishing said lamp and permitting telephonic intercommunication.

10. A composite electric signaling and inter-communicating system, including: a source of alternating current; means including a full-wave rectifier for supplying a source of direct current; a first relay connected with and maintained operated by said direct current; a make-before-break switch; a plurality of alarm bells and telephones connected in multiple series; a circuit for said bells and telephones closed through said switch by the operation of said first relay; a sub-cycle ringer connected with said alternating current; a second relay; an alarm key; a circuit for operating said second relay closed by the contact points of said alarm key; a circuit connecting said ringer with said bells, for ringing the same, said circuit closed by the operation of said second relay; a closed switch-hook in said alarm key circuit, whereby said second relay is restored by opening said switch-hook; a battery; a battery-ringing converter; a circuit connecting said battery and said converter, said circuit closed by said make-before-break switch; a third relay; a circuit for operating said third relay closed by said alarm key; and a circuit connecting said converter with said bells and telephone circuit, said circuit closed by the operation of said third relay, whereby failure of said alternating current restores the first said relay, thereby connecting said third relay and said battery and said converter to said system through said make-before-break switch.

11. A system as claimed in claim 10: a fourth relay; and a normally closed circuit connecting said fourth relay with said direct current and said alarm key circuit for operating said fourth relay, whereby opening said closed circuit restores said fourth relay closing said alarm key circuit for operating said second relay and sounding an alarm.

12. A system as claimed in claim 11: a timer; and a normally open circuit connecting said timer with said fourth relay and said closed circuit, said open circuit closed at predetermined times by said timer to maintain said fourth relay operated when said closed circuit is opened, thereby preventing the sounding of an alarm.

13. A system as claimed in claim 12: an alarm lamp; and a circuit for said lamp closed by the operation of said second relay.

14. A system as claimed in claim 13: a double wound relay in said bells and telephone circuit normally operated by the operation of the first said relay; a marginal relay in said bells and telephone circuit normally unoperated; a rheostat; a circuit connecting said marginal relay and said rheostat in series with said telephone circuit closed by the operation of said switch-hook for establishing a balanced impedance over said telephone circuit; a trouble-indicating lamp; a first circuit for said lamp closed by

said marginal relay; and a second circuit for said lamp closed by restoring said double wound relay.

15. A system as claimed in claim 14: an emergency lamp; and a circuit for said emergency lamp closed by the operation of said make-before-break switch.

16. A system as claimed in claim 15: a first buzzer; a first circuit for said first buzzer closed by said marginal

relay; and a second circuit for said first buzzer closed by restoring said double wound relay.

17. A system as claimed in claim 16: a second buzzer; and a circuit for operating said second buzzer closed by the operation of said make-before-break switch.
